UNITED STATES PATENT OFFICE.

WILLIAM SMITH, OF PITTSBURG, PENNSYLVANIA.

IMPROVEMENT IN COAL-OIL RETORTS.

Specification forming part of Letters Patent No. 23,719, dated April 19, 1859.

To all whom it may concern:

Be it known that I, WILLIAM SMITH, of Pittsburgh, in the county of Allegheny and State of Pennsylvania, have invented a new and useful Improvement in Coal-Oil and Gas Retorts; and I hereby declare that the following is a full, clear, and exact description of the same.

To enable others skilled in the art to make and use my invention, I proceed to describe the construction and operation of my improved retort, taking reference to the accompanying drawings, making a part of this specification, in which—

Figure 1 is a longitudinal vertical section; Fig. 2, a transverse vertical section of the whole retort, and Fig. 3 a separate view of the hollow shaft and its arms.

In all these figures the same letters of reference indicate like parts.

A is the retort. It is of cylindrical form, and is supported by the front and back plates, B B', which form a part of the furnace for heating the retort. This furnace is not represented in the drawings, as it has no relation to my improvement, any known furnace arrangement by which a proper circulation of the heat around the retort is effected will answer the purpose. The fire-door of the furnace is indicated at a, Fig. 1.

C C' are the heads of the retort, bolted to it by a number of bolts, b b'.

c is the man-hole or feeding-opening, (provided in the head C,) through which the retort is charged with the coal or other substance to be distilled, and through which also the residue of the substance is removed after the distillation. The feeding-hole is closed in the ordinary way by a lid kept firmly down by a set-screw, d.

D is a hollow shaft passing tightly through the center of the heads C C'.

h h are hollow arms, tapped or screwed into the shaft D so that their hollow spaces communicate with that of the shaft. The arms extend close to the cylindrical inside surface of the retort, however, without touching it. The number of arms or the distance they are apart, and also the mode of their distribution around the shaft, or their position in relation to each other, may be changed variously and in any manner which may be deemed to be best suited to the nature of the substance to be distilled, some substances requiring more, others less, agitation. Thus

Fig. 3 shows the arms set close together and arranged in a spiral line around the shaft, which mode has the advantage that the arms enter and pass through the liquid or semi-liquid mass in the retort in regular succession, whereby the resistance offered to the motion of the shaft will be uniform and the agitation very regular.

In distilling coal for the purpose of producing gas the heat in the retort is of such a high degree that it would affect the strength of the arms h h and be injurious to them in regard to durability. To obviate this, I make the shaft and arms hollow, as above mentioned, and conduct a current of air or water through them, which is introduced through one journal of the shaft and passes out through the other, as indicated by arrows in Fig. 1. By this means the shaft and arms are kept sufficiently cool, so as not to be injured by the heat in the retort. The gas or oil produced in the retort passes off through one or more pipes, i i, provided in the head C' of the retort, which communicate with a reservoir or condenser, as the case may be.

The operation of my improved retort is very simple: After the retort is properly charged through the feeding-opening c with the coal or other substance to be distilled, the shaft is set into a slow rotating motion; or, if such should be preferred, into an oscillating or vibrating motion. This motion of the shaft is derived from any motive power by means of wheel-gearings or other well-known mechanical means. None of these means are represented in the accompanying drawings, as they have no reference to the arrangement of my improved retort.

I am aware that shafts exposed to heat have been made hollow and water or air conducted through them for keeping them cool. I therefore do not claim this broadly; but,

Having thus described my invention, I claim as new in the construction of coal-oil retorts and desire to secure by Letters Patent—

The making of the agitating-arms h hollow, and to communicate with the hollow shaft D, for the purpose of cooling them, by means of the current of air or water passing through the said shaft, substantially as herein set forth.

WM. SMITH.
